UNITED STATES PATENT OFFICE

ARTHUR J. WILLS, OF BROOKFIELD, MASSACHUSETTS.

MEANS FOR ATTACHING HEELS.

1,227,722.

Specification of Letters Patent. Patented May 29, 1917.

Application filed March 29, 1916. Serial No. 87,651.

To all whom it may concern:

Be it known that I, ARTHUR J. WILLS, of Brookfield, in the county of Worcester and State of Massachusetts, a citizen of the 5 United States, have invented a new and useful Improvement in Means for Attaching Heels, of which the following is a specification.

Rubber heels for the attachment of which 10 my invention is particularly intended, are usually made with nail recesses extending into the heel a short distance from its wearing surface, each reinforced at its bottom by a metal washer, which is molded into the 15 heel at the time the heel is vulcanized, and should be parallel with the upper and under surfaces of the heel. There is always some difficulty in properly locating these washers in the body of the heel during the molding 20 and vulcanizing process as they are apt to be displaced in the mold as the plastic rubber is forced around them. Moreover, the cost of the washers and labor of installing 25 them is considerable. The purpose of these washers is to hold the nail head from pulling through the heel when it is attached to the shoe, serving as a reinforcement to the head of the nail.

My invention comprises a mode of attachment as well as a new heel, the heel having 30 no washer in it and the head of the nail, which is my invention, being of a character to spread and serve the purpose of the washer heretofore used.

My invention will be understood by reference to the drawings, in which it is shown 35 in its preferred form.

Figure 1 is an enlarged elevation of a nail embodying my invention,

40 Fig. 2 being a top view thereof,

Fig. 3 an elevation showing the condition of the nail head after the nail has been driven,

Fig. 4 being a top view thereof.

45 Fig. 5 shows the preferred heel construction to be used with my nail, the nail being in position to be driven into the recess.

Fig. 6 shows the first position of the nail head within the recess,

50 Fig. 7 being its second position, and

Fig. 8 showing the nail, the heel and the shoe in final position, these last three views illustrating the co-operation of the recess with the nail head in the process of 55 driving.

Fig. 9 is a nail embodying my invention which has but a single prong.

A is the shank of the nail, B being the head. Preferably integral with the head are, as shown, three projections *b* which when the nail is first made project downward and are bent slightly outward as at *b*¹, all as shown in Fig. 1 and Fig. 2, which is a top view thereof. C is the heel which has a recess *c* having preferably a center depression *c*¹, therein, the purpose of which is to receive the point of the nail and so center it when it is to be driven, this depression being desirable but not necessary. It will be noted that the recess *c* is slightly larger than the diameter of the circle surrounding the tips *b*¹ of the projections *b* so that when the nail has been partially driven, as shown in Fig. 6, the projections *b* will all be within the recess *c* clearing its side wall, their tips 75 resting on the bottom of the recess. As the nail is still further driven down it takes the position shown in Fig. 7 where it will be noted that the ends *b*² of the projections *b*, because of their outwardly-projecting character, have been turned outwardly by the bottom of the recess *c* and have been flattened out more or less so that they are driven into the rubber, and in their final position, as shown in Fig. 8, they project upward, being bent during the further process of driving. In practice these nails are driven by a machine and at one blow or by pressure, the above views being illustrative merely of the operation of the parts of the nail. In 85 Fig. 8 it will also be noted that the tip *a* of the nail has been clenched into the shoe in the manner usual, so that in this case the shoe and the heel are gripped together by the clenching point of the nail which engages the inner surface of the shoe, and the projections *b* which form part of the head, so that they are firmly held without any 90 reasonable possibility of being torn apart.

I do not mean to limit myself to a nail 100 head having the precise number of projections shown as one or more may be used to accomplish the desired result (see Fig. 9 where one projection *b*² is shown). My nail accomplishes by itself what has heretofore 105 been accomplished by a nail and a washer embedded in and forming part of the heel. The projections, if not a part of the nail head, should be made of reasonably flexible material so that they may perform the bend- 110

ing function which is necessary to make them bend properly as shown. In using the term "shoe" I mean to include the leather heel or sole or any part to which the rubber heel may be attached. I use the term "rubber heel" by way of illustration as my nail may be used for other purposes than heel attaching, and other rubber or plastic articles may be applied by it.

10 What I claim is:—

1. The nail above described having a head with one or more flexible prongs extending downwardly therefrom, the ends of said prongs projecting outwardly.
- 15 2. The nail above described having a head with one or more flexible prongs extending downwardly therefrom, the ends of said

prongs projecting outwardly, in combination with an article having a recess the lower surface of which is adapted to engage the outwardly-projecting ends of said prongs and flatten them out, whereby they will be driven laterally into said article when the nail is driven therethrough.

3. In combination, a rubber heel, a shoe, 25 and a nail passing through said heel and into said shoe and clenched at its point, said nail having a head with prongs projecting at right angles thereto into the interior of said heel, whereby said heel will be attached 30 to said shoe by said prongs and said clenched point.

ARTHUR J. WILLS.
